United States Patent Office.

JOSEPH TRENT, OF MILLERTON, NEW YORK.

Letters Patent No. 60,806, dated January 1, 1867.

IMPROVEMENT IN LIQUID MEASURES.

The Schedule referred to in these Letters Patent and making part of the same.

TO ALL WHOM IT MAY CONCERN:

Be it known that I, Joseph Trent, of Millerton, in the county of Dutchess, and State of New York, have invented a new and improved "Measurer and Tunnel combined;" and I do hereby declare that the following is a full and exact description thereof, reference being had to the accompanying drawings, and to the letters of reference marked therein, on which—

Figure I represents the "measurer and tunnel combined," with the funnel adjusted for use.

Figure II is an elevation representing the same, with the funnel, when not in use, adjusted as a cover.

Figure III is an isometric view of the same, with the funnel adjusted for use, showing the strainer in the nozzle of the can.

Explanation of Figures.

A is the body of the can; B the funnel; C the nozzle; D the glass tube gauge or meter; E the handle; F the strainer in the nozzle of the can; H the double-jointed hinge, by means of which the tunnel is adjusted for use and set in position as a cover; I I' I", bands securing the gauge D to the body of the can, and also serving as indices on the gauge.

The manner in which the "measurer and tunnel combined" is used is as follows, viz: The cover or tunnel B having been removed, as in Fig. I, the fluid is poured in at the top of the can; or replacing the tunnel in the position of a cover, as in Fig. II, the fluid remains, as in any covered vessel, protected from air and dust, and may be poured through the strainer F and nozzle C into any vessel which has a large or flaring orifice in the top, as a pitcher or mug. If, now, it is desired to pour the fluid into any other vessel with a small opening, or such a one as necessitates the use of a tunnel, the cover B is again detached from its position upon the can (as seen in Fig. II) and adjusted by means of the double-jointed hinge H so as to assume the position set forth in Fig. I, the tunnel B coming so into position under the nozzle that on pouring the fluid passes directly from the nozzle through the tunnel. The glass tube gauge D opening at its extremities through metallic tubes (by means of which it is made fast to the can) into the body of the can, the fluid, on being poured into the can, rises simultaneously in the can and the gauge. As the fluid enters the tube from the bottom of the can, the gauge is kept free from froth and impurities, which float on the surface, and an accurate measure of the quantity of fluid is thus furnished by means of the graduated scale or indices on the meter.

The advantages of the "measurer and tunnel combined" consist in, that fluids can be poured from one and the same can into vessels of any shape whatever; that the tunnel or cover, being attached to the can, is not liable to be lost or misplaced; the greater compactness arising from uniting the tunnel and cover in one; that the fluid can be measured accurately, and transferred from one receptacle to another without the necessity of employing a variety of vessels or utensils.

Claim.

I claim, and desire to secure by Letters Patent—

The combination of the can A and the tunnel B, and the double-jointed hinge H, substantially as arranged and described.

JOSEPH TRENT.
